(57) **CLAIM**

The ornamental design for a display screen with graphical user interface, as shown and described.

DESCRIPTION

FIG. 1 is a front view showing a first embodiment of a display screen with graphical user interface;
FIG. 2 is a front view of a second embodiment thereof;
FIG. 3 is a front view of a third embodiment thereof;
FIG. 4 is a front view of a fourth embodiment thereof;
FIG. 5 is a front view of a fifth embodiment thereof;
FIG. 6 is a front view of a sixth embodiment thereof;
FIG. 7 is a front view of a seventh embodiment thereof; and,
FIG. 8 is a front view of an eighth embodiment thereof.
The broken lines in the drawings illustrate unclaimed portions of the display screen with graphical user interface and form no part of the claimed design.
